UNITED STATES PATENT OFFICE.

BENJAMIN GREEN DEVOE, OF LIMA, OHIO.

JAR-COVER.

SPECIFICATION forming part of Letters Patent No. 684,799, dated October 22, 1901.

Application filed September 1, 1900. Serial No. 28,826. (No model.)

To all whom it may concern:

Be it known that I, BENJAMIN GREEN DEVOE, a citizen of the United States, residing at Lima, in the county of Allen and State of 5 Ohio, have invented new and useful Improvements in Jar-Covers, of which the following is a specification.

My invention relates to improvements in jar or can covers, and more particularly to 10 that class of covers designed to seal the can or jar in a hermetical manner.

The objects of the invention are, first, to provide an improved cover so constructed as to hermetically seal the can and protect the 15 contents from the deleterious effects of the air; second, to provide improved means whereby the cover may be securely locked in position until it is desired that it should be removed, and, third, to provide an improved 20 cover which will be simple in construction, cheap of manufacture, and durable and effective in use.

I attain the above-enumerated objects by the construction, arrangement, and aggroup- 25 ment of parts to be more fully described in the following specification, and the novelty of which will be particularly pointed out in the claims.

I have fully and clearly illustrated my in- 30 vention in the accompanying drawings, wherein—

Figure 1 is a perspective view of a jar pro- 35 vided with my improved cover. Fig. 2 is a longitudinal sectional view thereof. Fig. 3 is a top plan view of the jar with the cover removed therefrom. Fig. 4 is a view of the bottom of my improved cover. Fig. 5 is a side 40 view in elevation of the cover; and Fig. 6 is a side view in elevation of the cover, showing the cam-faced flanges.

Referring to the drawings, 1 designates a jar of any suitable form, to which my invention is applied. The interior of the mouth of this jar 1 is provided with an annular shoulder 2, having its inner circumference formed 45 with segmental recesses 3. This shoulder 2 is formed so as to be provided with an annular recess or groove 4 and inner raised portions or beads 5. The groove 4 is adapted to receive and retain any suitable packing, as at 6. I prefer to make this packing of a composition of cotton or like material and par-

affin or beeswax, which at once forms a substance that is yielding to pressure and well adapted to the use intended. In the groove 55 4 and upon the surface of the packing 6 I place a packing-ring 7, of yielding material, preferably of rubber, which adds materially in hermetically sealing the closure and protects the packing 6 from such liquids or other 60 substance as may pass through the mouth or open end of the jar.

The cover consists of a cylindrical portion 8, the upper surface of which is provided with an annular flange 9. The upper surface of 65 the cover is provided with an elongated socket 10, adapted to receive a suitable instrument or tool for turning the cover to either lock or unlock the same. The under face of the annular flange 9 is grooved, so as to form an 70 annular recess 11 and an annular depending bead 12. This bead 12 is adapted to fit down closely upon the surface of the rubber packing-ring 7. In the recess 11 is placed a suitable packing 13, adapted to rest upon the upper surface of the raised portions or beads 5 of the shoulder 2. It will be seen from the 75 above description, taken in connection with the drawings, that a double means is afforded for hermetically sealing the jar-cover. 80

The lower portion of the cylindrical cover 8 is provided with laterally-projecting flanges 14, of the same length as that of the segmental recesses 3 and adapted to register therewith. These lateral projections or flanges 4 85 have their upper surfaces curved or cam-shaped, as at 15, so as to better grip the under surface of the shoulder 2.

When it is desired to seal the jar, the cover is placed in the mouth of the jar with the 90 lateral projections 14 opposite the segmental recesses 3 in the annular shoulder 2. The cover is then pushed downward and a suitable instrument placed in the elongated recess 10, whereby the cap is given a quarter-turn in either direction, so as to bring the laterally-projecting flanges 14 under the shoulder 2 to lock the cover securely in position. By thus turning the cover the cam-surfaces 15 will cause the bead of the annular flange 100 9 to press upon the packing 7 in the annular groove 4 and the inner beaded portions 5 of the shoulder 2 to impinge against the packing in the groove of the cap or cover. It

will thus be perceived that by the above-described construction I provide a cover simple in construction which will securely and hermetically seal the jar.

5 What I claim is—

1. The combination with a jar, provided with an internal laterally-projecting flange having segmental recesses formed therein and a groove in the upper face thereof, of a cover 10 provided with an upper annular flange, the under face of which is formed with a groove adapted to receive any suitable packing; and lower segmental, laterally-projecting flanges at the base of said cover, adapted to enter 15 the segmental recesses in the shoulder of the jar, and to be turned thereunder to lock the cover in position.
2. The combination with a jar, provided with an internal, laterally-projecting flange 20 having segmental recesses formed therein, and a groove in the upper face thereof adapted to receive any suitable packing, of a cover provided with an upper annular flange, the under face of which is provided with an annular depending bead, adapted to fit closely 25 upon the surface of the packing in the groove of the flange in the shoulder of said jar; and lower segmental, laterally-projecting flanges at the base of said cover, adapted to enter 30 the segmental recesses in the internal shoulder of the jar, and to be turned thereunder to lock the cover in position.
3. The combination with a jar, provided with an internal, laterally-projecting flange 35 having segmental recesses formed therein, a groove in the upper face thereof adapted to receive any suitable packing, and an inner annular bead; of a cover formed with an upper annular flange, the under face of which 40 is provided with an annular groove adapted to receive a packing material, arranged so as

to rest upon the bead on the flange of the jar; an outer peripheral depending bead upon the under face of the upper flange of the cover, adapted to fit closely upon the packing in the groove in the flange of the jar, segmental, laterally-projecting flanges at the base of the cover, formed to enter the recesses in the flange of the jar, and to be turned thereunder to lock the cover in position. 45 50

4. The combination with a jar, provided with an internal laterally-projecting flange having segmental recesses therein, a groove in the upper face thereof, adapted to receive a packing of any suitable material, a rubber packing-ring in the groove and on the surface of the packing material and adapted to protect the same from moisture, &c., and an inner annular bead, of a cover formed with an upper annular flange, the under face of which is provided with an annular groove adapted to receive a packing material, arranged so as to rest upon the bead on the flange of the jar; an outer peripheral depending bead upon the under face of the upper flange of the cover, adapted to fit closely upon the packing on the flange of the jar, segmental, laterally-projecting flanges at the base of the cover, provided with cam-surfaces 60 65 70 75 adapted to enter the segmental recesses in the flange of the jar, and an elongated socket in the upper face of the cover adapted to receive a suitable tool for turning the cover into a locked position.

In testimony whereof I affix my signature in presence of two witnesses.

BENJAMIN GREEN DEVOE.
